(57) **CLAIM**

The ornamental design for a fill limit venting valve with high shut-off height, as shown and described.

DESCRIPTION

FIG. 1 is a top perspective view of a fill limit venting valve with high shut-off height in accordance with the present teachings.

FIG. 2 is a bottom perspective view of the fill limit venting valve with high shut-off height of FIG. 1.

FIG. 3 is a top view of the fill limit venting valve with high shut-off height of FIG. 1.

FIG. 4 is a bottom view of the fill limit venting valve with high shut-off height of FIG. 1.

FIG. 5 is a front view of the fill limit venting valve with high shut-off height of FIG. 1.

FIG. 6 is a rear view of the fill limit venting valve with high shut-off height of FIG. 1.

FIG. 7 is first side view of the fill limit venting valve with high shut-off height of FIG. 1; and,

FIG. 8 is second side view of the fill limit venting valve with high shut-off height of FIG. 1.

The broken line showing portions of the fill limit venting valve with high shut-off height form no part of the claimed design.

1 Claim, 5 Drawing Sheets
